UNITED STATES PATENT OFFICE.

JOHN O. DAVIS, OF HARTFORD, CONNECTICUT.

PUMP.

SPECIFICATION forming part of Letters Patent No. 412,480, dated October 8, 1889.

Application filed January 6, 1887. Serial No. 223,505. (No model.)

To all whom it may concern:

Be it known that I, JOHN O. DAVIS, of Hartford, in the county of Hartford and State of Connecticut, have invented a certain new and useful Improvement Pertaining to Pumps, of which the following is a description, reference being had to the accompanying drawings, wherein—

Figure 1 is a front view of an attachment 10 to a double-acting lifting and forcing pump embodying my said improvement. Fig. 2 is a top view of the same attachment. Fig. 3 is a view of the same attachment in longitudinal section on plane X X, the two pumps being denoted in outline only. Fig. 4 is a view 15 of the same attachment in vertical cross-section on the plane Y Y, with the pump denoted in outline simply, as such view would show but one of the pumps. This section 20 cuts through one of the check-valves. A similar sectional view of the other check-valve is just the same.

This improvement pertains to a pump apparatus in which there are two pumps, each 25 a lifting and forcing pump, used generally for forcing water into steam-boilers under pressure in a substantially continuous stream, and the object of the improvement is to permit the two pumps to run regularly and continuously at a regular and uniform speed, and yet adjust and control the amount of water 30 they shall feed or force into a steam-boiler or the like, without varying the strain upon the pumps or causing them to pound when the 35 outlet is closed or reduced; and my improvement consists in a double-cylinder lifting and forcing pump in combination with a "by-pass" valve of peculiar construction, as more particularly hereinafter described, and pointed 40 out in the claim.

The letter *a* denotes one of the pumps proper as a whole, of which there are two alike, as indicated in outline in Fig. 3.

The letter *b* denotes a suction-duct leading 45 to the barrel of the pump *a*, of which suction-ducts there are two just alike. Each suction-duct is furnished with a check-valve *c*, two of which are just alike.

So far I have described what is old. I will 50 now describe the new feature. The lower part of the frame-work is chambered out and forms a common reservoir for the supply of

water to both pumps, the inlet-pipe leading into this chamber and both the suction-ducts, in which the check-valves are located, leading out of it. The two suction-ducts *b* are connected by the communicating-duct *d*, which is furnished with an adjustable stop-valve *e*, the stem of which is threaded for a short distance and fits a threaded socket in 60 the frame-work, and then passes through an ordinary stuffing-box and terminates in a handle, whereby this connecting-duct may be wholly closed or opened to any desired degree. In the ordinary form of pumping device the pistons in the pump-cylinder reciprocate alternately with a regular and uniform motion, which causes the check-valves to rise and fall alternately with a regular and uniform motion that feeds a certain amount of 65 water each time they reciprocate, which, if the outflow is cut off or checked in any manner, causes a severe strain upon the pumps by back-pressure, and this oftentimes seriously injures the pumps if they are not stopped. 75

The operation of my improved device is as follows: When the piston rises, the liquid is drawn into the chamber *b* from the supply, the suction lifting the valve *c* and allowing the water to flow around it. When the piston 80 descends, the valve *c* is closed and the liquid is forced into the boiler or other receiver. It is desirable to keep the pump in operation at a uniform speed, but not always necessary to supply the same quantity of water to a boiler, 85 and to overcome any back-pressure produced by not carrying away the full supply from the pump a duct *d* is provided which communicates with the suction-duct of the other pump, and the surplus water escapes through this 90 way *d* in any quantity desired. This is regulated of course by the position of the valve *e*. Thus by regulating the size of the opening around the valve *e* the amount of feed-water can be regulated and the pressure on the 95 pumps maintained constant, regardless of the amount of liquid required by the boiler or other receiver, and the surplus water used to supply the other pump. In case no water is needed, the pumps can still keep in motion, 100 but merely force the water from one barrel to the other through the connecting-duct.

I claim as my improvement—
In combination with a pair of suction and

forcing pumps, a frame-work chambered out to form a common reservoir to supply both pumps, and having a suction-duct leading from the chamber to each pump, a valve seated in each suction-duct with an upward-projecting stem fitting a socket in the frame-work to insure its seating itself properly, a channel leading from one suction-duct to the other, a valve seated in an enlargement of said channel, said valve having a portion of its stem threaded to fit a threaded socket in

the frame-work, with its end projecting beyond the frame-work and terminating in a handle, whereby the capacity of the connecting-channel may be regulated by turning the handle of the valve-stem, substantially as described, and for the purpose specified.

JOHN O. DAVIS.
